DANIEL H. KRAUSER, OF POTTSVILLE, PENNSYLVANIA.

Letters Patent No. 102,947, dated May 10, 1870.

IMPROVED COUNTER SEAT.

The Schedule referred to in these Letters Patent and making part of the same.

To all whom it may concern:

Be it known that I, DANIEL H. KRAUSER, of Pottsville, in the county of Schuylkill and State of Pennsylvania, have invented a new and valuable Improvement in Counter Seats; and I do hereby declare that the following is a full, clear, and exact description of the construction and operation of the same, reference being had to the annexed drawings making a part of this specification, and to the letters and figures of reference marked thereon.

Figure 1 of the drawings is a representation of my invention in perspective, the seat being drawn out.

Figure 2 is a similar view, with the seat folded back.

Figure 3 is a vertical sectional view.

My invention relates to counter seats for stores, and consists in the construction of slotted brackets to be attached to the counter, and designed to operate in conjunction with a pivoted brace to support the seat when drawn out, or to permit it to be readily folded up against the front of the counter, out of the way.

The letter A, of the drawings, designates the seat or cushion.

B is a brace pivoted to the front thereof, and forked at its lower end to embrace the slotted bracket C. The lower ends of the fork are connected by the pin *a*, which plays in the slot of this bracket.

D D are larger brackets, arranged on each side of the small bracket C, and are designed to support the rear of the seat. They, as well as the bracket C, are secured to the wall of the counter, in case there is

such a wall. If not, standards can be made for them and secured to the floor.

Arms *b b* are fastened to the bottom of the seat A, and are provided with the studs or pins *c c*, arranged to play in the slots of the brackets D D.

A bend is formed in the upper part of the slot of each bracket, in such a manner that a recess or ledge, *d*, is provided to support the studs *c c* and pin *a* when the seat is drawn out. In the slot of the central lower bracket this ledge is turned toward the counter, in order that it may better serve as a bearing for the pin *a* of the brace. But the slots of the brackets D D are bent outward from the counter to receive the studs *c c*, which are forced in that direction when pressure is applied to the seat.

What I claim as my invention, and desire to secure by Letters Patent, is—

The adjustable counter seat herein described, provided with pivoted brace B, arms *b*, journals *c*, and slotted brackets C D, arranged to permit the seat to be drawn out horizontally or folded vertically against the counter-front, as specified.

In testimony that I claim the above, I have hereunto subscribed my name in the presence of two witnesses.

DANIEL H. KRAUSER.
